UNITED STATES PATENT OFFICE.

HUGO BISCHOFF, OF BERLIN, AND ARMAND MIEG, OF LEIPSIC, SAXONY,
GERMANY.

PROJECTILE.

SPECIFICATION forming part of Letters Patent No. 394,673, dated December 18, 1888.

Application filed August 6, 1887. Serial No. 246,251. (No model.)

To all whom it may concern:

Be it known that we, HUGO BISCHOFF, a subject of the King of Bavaria, and a resident of Berlin, Prussia, Germany, and ARMAND MIEG, a subject of the King of Bavaria, and a resident of Leipsic, Saxony, Germany, have invented new and useful Improvements in Projectiles, of which the following is a specification.

10 The invention relates to projectiles consisting of a hard-metal casing containing lead or other similar material.

The object of the invention is to provide a new and improved case-projectile having a 15 guide-ring of soft metal to prevent rapid wear of the grooves of the rifle-barrel, and at the same time to press the filling tightly into the metal casing.

10 The invention consists in the construction 20 hereinafter described, and specifically pointed out in the claim.

Reference is to be had to the accompanying drawings, forming a part of this specification, in which similar letters of reference indicate 25 corresponding parts in all the figures.

Figure 1 is a sectional elevation of a case-projectile without a guide-ring. Figs. 2, 3, and 4 are sectional elevations of case-projectiles provided with guide-rings before being 30 pressed in and illustrate various forms. Figs. 5 to 11 are sectional elevations of our improved case-projectiles, illustrating various forms; and Figs. 12 to 17 are side elevations of the same, illustrating various forms.

35 Case-projectiles are specially designed for small-arms, and consist of a strong hard-metal casing, *a*, containing a filling, *b*, of lead or other suitable material, as illustrated in Fig. 1. Such a projectile, when pressed into the 40 bore of a rifle, would naturally destroy the grooves or windings when fired through the same; and to obviate this objection we provide each projectile with one or more soft-metal rings, *c*, which are pressed into the 45 hard-metal casing *a*. To accomplish this, we place the soft-metal ring or rings *c* on the hard-metal casing *a*, and then place the projectile in a suitable press, of any approved construction, so that a high pressure is exerted against the soft-metal ring or rings *c*, which are thus forced into the hard-metal 50 casing *a*, as illustrated in Figs. 5 to 11. The part of the hard-metal casing on which the ring *c* rests is pressed into the filling *b*, which

is thus pressed firmly and tightly in the casing *a*. The dies for pressing the rings *c* into the hard-metal casing *a* are of suitable shape, so as to press part of the ring *c* flush with the metal casing *a*, and at the same time leave an annular projection, *c'*, as illustrated in 60 Figs. 6, 7, and 8. The dies of the press may also be of such a shape as to press the ring into conical form, as illustrated in Figs. 9 and 10; or the dies may be made of other forms of suitable cross-section.

65 It will be seen that part of the soft-metal ring *c*, projecting around the exterior of the hard-metal casing *a*, fits into the groove of the rifle-barrel, thus guiding the projectile through the barrel when fired, and, as the said ring is of soft metal, the grooves in the barrel are not injured.

In case *a* a space is formed between the pressed-in ring *c* and the respective part of the hard-metal casing *a*, as illustrated in Fig. 75 11, then the projectile receives, by means of a press, a pressure against its bottom, so that the filling *b* forces the respective part of the hard-metal casing *a* into the empty space and tightly against the pressed-in ring *c*.

80 It will be seen that our improved projectile, having a soft-metal ring, does not injure the grooves of the rifle-barrel, and by pressing the said soft-metal ring into the hard-metal casing we force the filling material tightly 85 into its casing.

Having thus fully described our invention, we claim as new and desire to secure by Letters Patent—

As an improved article of manufacture, a 90 projectile consisting in a soft-metal core having a circumferential groove, a hard-metal case inclosing the sides and point of the said core and provided with a circumferential depression, the internal ridge or shoulder formed 95 thereby closely fitting in the said groove of the core, and a guide-band fitting the said circumferential depression in the case and having a projecting part extending beyond the sides of the case to engage the grooves of the 100 gun-barrel, substantially as set forth.

In testimony whereof we have signed our names to this specification in the presence of two subscribing witnesses.

HUGO BISCHOFF.

Witnesses: ARMAND MIEG.
